DESIGN FOR A CHAIR

Jack B. Cunningham, North Hollywood, Calif.

Application February 24, 1947, Serial No. 137,109

Term of patent 3½ years

(Cl. D15—1)

To all whom it may concern:

Be it known that I, Jack B. Cunningham, a citizen of the United States, residing at North Hollywood, in the county of Los Angeles and State of California, have invented a new, original, and ornamental Design for Chair, of which the following is a specification, reference being had to the accompanying drawing, forming part thereof.

Fig. 1 shows a perspective view of the chair as viewed from the front; and Fig. 2 shows a rear elevational view of the same.

I claim:

The ornamental design for a chair, as shown.
JACK B. CUNNINGHAM.
